BUTTONHOLE AND METHOD OF MAKING
THE SAMEDave Zilinsky, New York, N. Y., assignor to The
Reece Button Hole Machine Company, Boston,
Mass., a corporation of Maine

Application June 12, 1933. Serial No. 675,336

6 Claims. (Cl. 2—277)

This invention relates to the formation of so-called piped buttonholes which are now in extensive use. In these buttonholes the usual buttonhole stitching is omitted, and the buttonholes 5 finished and reinforced by folds of a separate piping fabric extending along their edges. Such piped buttonholes have heretofore, so far as I am aware, been made by hand: an expensive operation frequently constituting a very considerable 10 part of the entire making cost of the garment. The present invention has for its objects to simplify and consequently cheapen the formation of such buttonholes and to provide a method and structure in accordance with which the seams by 15 which the piping fabric is secured to the main fabric of the garment are completely concealed at the face of the latter while effectively holding the parts in place.

These and other objects and advantages of the 20 invention will best be understood from the following description of a preferred mode of carrying the latter into effect, as illustrated in the accompanying drawing. It will be understood, however, that the particular constructions and 25 operations described and shown have been chosen for purposes of exemplification merely and that the invention, as defined by the claims hereunto appended, may be otherwise practiced without departure from the spirit and scope thereof.

30 In said drawing:—

Fig. 1 is a perspective view showing the initial attachment of the piping fabric to the main or body fabric of the garment.

Fig. 2 is a corresponding transverse section.

35 Fig. 3 is a sectional perspective view illustrating the slitting of the fabrics.

Fig. 4 is a view of the work after attachment and slitting, looking from the back or reverse side of the main fabric.

40 Figs. 5 and 6 are sectional views illustrating the turning of the buttonhole.

Fig. 7 is a sectional perspective view showing the parts after turning.

Fig. 8 is a view of the completed buttonhole, 45 looking from the front or face of the main fabric.

Fig. 9 is a similar view looking from the back or reverse side.

The main or body fabric in which the buttonhole is to be formed is shown at 15, the front or 50 face side thereof being indicated by the numeral 16 and the back or reverse side by the numeral 17. The piping fabric is shown at 18 and is supplied in single pieces of sufficient size to finish individual buttonholes. Each piece is folded 55 over upon itself in opposite directions along two

preferably straight parallel lines 19 intermediate the edges 20 thereof to form two oppositely extending folds or pleats 21, leaving said edges upstanding, as shown in Fig. 1. The folds 21 are secured to the face 16 of the main fabric 15 by 60 two lines of stitching 22 spaced from the edges 19 of said folds and passing through both layers of the latter but through only one layer or thickness of the main fabric (Figs. 1 and 2).

The main and piping fabrics are cut to form 65 registering slits 23 and 24, respectively, of a length corresponding to the length of the desired buttonhole. This slitting may be done prior to, simultaneously with, or subsequent to the stitching of the seams 22. Accurate registration of the 70 slits can be most conveniently assured by slitting the fabrics simultaneously with or subsequent to their attachment to each other. Preferably the slitting is done subsequent to the stitching operation, as by means of a suitable 75 slitting knife 25 conventionally illustrated at 25 in Fig. 3.

After the piping fabric has been secured to the main fabric with the slits 23 and 24 in register, the free edges 20 of the piping fabric are folded 80 inwardly and inserted into said slits, as shown in Fig. 5, and the entire piping fabric turned therethrough, as illustrated in Fig. 6, resulting in the structure shown in Fig. 7. This operation results in the formation of inturned portions 26 85 in the main fabric 15 at the back or reverse side 17 thereof along the edges of the slit 23 therein, which portions are secured to the folds 21 of the piping fabric by the stitches 22 which pass through both layers of the folds in the piping 90 fabric but through the inturned portions only of the main fabric, leaving the folds projecting slightly beyond the longitudinal edges of the slit 23, as shown in Fig. 8, to constitute the desired piping. As shown most clearly in Fig. 4, the lines 95 of stitching 22 are substantially equal in length to the slits 23 and 24, leaving the end portions 30 of the piping fabric free in order to facilitate the complete turning of said piping fabric through 100 said slits as described.

Since the stitching 22 passes only through the inturned portions 26 of the main fabric, it is wholly concealed from the face of the main fabric, whose appearance is therefore not marred thereby, and the color and texture of the thread 105 employed is immaterial. Since, however, said stitching passes through both layers of the folds 21, it tends to hold the body of the piping fabric flat at the back of the main fabric, so that no additional stitching through the main fabric is 110

required for this purpose. In fact, the stitching 22 is the only stitching necessary, particularly where a lining is employed, but it is preferred to complete the work by additional lines of stitching 27 extending transverse to the stitching 22 and slit 24 at the ends of the latter, said stitching 27 passing through the piping fabric only (including both layers of the folds 21 therein) and assisting in holding the latter in its desired flat, folded 10 condition.

For convenience and brevity, the term "fabric" is used herein to designate the materials 15 and 18, but I wish it understood that this expression is not to be taken as limited to textile materials, 15 but that it is intended to include any and all materials, such, for example, as leather, suitable for the purposes in question.

I claim:

1. A piped buttonhole comprising a main fabric and a piece of piping fabric, said fabrics having 20 registering slits, said main fabric having in-turned portions along the edges of the slit therein, and said piping fabric being folded upon itself along two lines at opposite sides of the slit there-in, and lines of stitching securing said fabrics 25 together adjacent the longitudinal edges of the buttonhole, said stitching passing through both layers of the folds in said piping fabric and through the in-turned portions only of said main fabric.

2. A piped buttonhole comprising a main fabric and a piece of piping fabric, said fabrics having 30 registering slits, said main fabric having in-turned portions along the edges of the slit therein, and said piping fabric being folded upon itself along two parallel lines intermediate the edges thereof and at opposite sides of the slit therein, lines of stitching securing said fabrics together 35 adjacent the longitudinal edges of the button-hole, said stitching passing through both layers

of the folds in said piping fabric and through the inturned portions only of said main fabric, and other lines of stitching transverse to said first-named lines at the ends of the buttonhole and passing through the piping fabric only.

80

3. The method of making piped buttonholes which includes folding a piece of piping fabric upon itself along two lines intermediate the edges thereof, stitching the folds so formed to a main fabric, cutting registering slits in the two fabrics between said folds, and turning the piping fabric through said slits.

85

4. The method of making piped buttonholes which includes folding a piece of piping fabric upon itself along two lines intermediate the edges thereof, securing the folds so formed to a main fabric by stitching through both layers of the folds and one layer only of the main fabric, cutting registering slits in the two fabrics between said folds, and turning the piping fabric through 95 said slits.

90

5. The method of making piped buttonholes which includes folding a piece of piping fabric upon itself along two lines intermediate the edges thereof, stitching the folds so formed to a main 100 fabric, cutting registering slits in the two fabrics between said folds, and turning the piping fabric and the attached adjacent edges of the main fabric through said slits.

100

6. The method of making piped buttonholes which includes folding a piece of piping fabric upon itself along two lines intermediate the edges thereof, stitching the folds so formed to a main fabric, cutting registering slits in the two fabrics between said folds, turning the piping fabric 110 through said slits, and sewing lines of stitching crosswise of the slits at the ends of the button-hole through said piping fabric only.
